MABEL BLACKMAN, OF NEW YORK, N. Y., ASSIGNOR OF ONE-HALF TO ESTELLE
McKEE AND ONE-HALF TO LILLIAN K. HOSIER, BOTH OF NEW YORK, N. Y.

TALKING-MACHINE NEEDLE.

Application filed October 21, 1921. Serial No. 509,281.

To all whom it may concern:

Be it known that I, MABEL BLACKMAN, a citizen of the United States, and a resident of the city of New York, in the county and State of New York, have invented certain new and useful Improvements in Talking-Machine Needles, of which the following is a full, clear, and exact description.

This invention relates to phonographs and in particular to the reproducing elements thereof.

A particular object of the invention is the production of a needle and associated part that will tend to eliminate the metallic chatter which is produced in that part of the needle that extends between the point thereof and the needle holding chuck.

Another object is to produce a needle encompassing element which can be sold separate from or with the needle, and which can be used with the ordinary reproducer without the necessity of changing the structure of the latter.

Drawings.

Figure 1 is a view in elevation of a portion of a phonograph including the reproducer and showing the association therewith of my anti-vibration device.

Figure 2 is a sectional elevation of the needle holding chuck and my device associated therewith, the needle being shown in full.

Figure 3 is a top plan view of my device.

Figure 4 is a modification, the showing being similar to that of Figure 2, with the exception that my device is made for permanent attachment to the chuck.

Description.

A phonograph comprising the usual universal arm 10 carrying the reproducer 11 is denoted generally by 12. Extending downwardly from the reproducer 11 is the chuck 13 in which the usual record engaging needle 14 is held through the medium of the set screw 15.

The needle 14 is of the usual type, which comprises enlarged portions 16 and 17, the

latter of which is inserted into the chuck 13, 50 both portions being connected by the reduced portion and the part 16 being gradually tapered to produce the needle point 18 which rides in the grooves of the record 19. The record 19 is supported on the usual 55 revolvable table 20.

The vibration deadener comprises a piece of semi-hard rubber 21 circular in shape and having a flat side 22 to allow for the operation of the set screw 15. The deadener 60 21 is tapered and the larger end 23 abuts against the under side of the chuck 13. A bore 24 is provided in the center of the deadener and the enlarged portion 16 of the needle is fixed therein, the bore gradually 65 getting larger as it extends upwardly from the portion 16 of the needle, so that the needle is free to have its proper vibration above said portion. In gripping the needle as it does, the deadener prevents the usual 70 vibration of the end thereof which produces the undesirable metallic sound now common in reproducing machines.

The needle and the deadener are sold as one unit, or the deadener may be slipped 75 over each needle as used.

In the modification the deadener is provided with an upwardly projecting ring portion 25 which partly surrounds the flange 26 formed on the chuck 13. It can 80 thus be seen that the deadener may be permanently attached to the chuck and form an element of the reproducer.

Claim.

A talking machine needle comprising an integral metallic stylus member adapted to be held firmly in the stylus chuck of said machine, a sound insulating member embracing said stylus member near its free 90 end, said insulating member being composed of a resilient material laterally extended and having an inverted frusto cone-shape, the base whereof is adapted to bear against the chuck for holding said needle 95 for absorbing a certain proportion of the vibration of said needle.

MABEL BLACKMAN.
